Emery, Parker PATENTED FEB 1 1870

ASSIGNOR TO THE

RUSSELL AND ERWIN MFG. CO.
DESIGN FOR A SASH LIFT.Witnesses,

M. J. Monroe
B. H. Scott

Inventor,

Emery Parker

United States Patent Office.

EMERY PARKER, OF NEW BRITAIN, CONNECTICUT, ASSIGNOR TO THE RUSSELL & ERWIN MANUFACTURING COMPANY, OF SAME PLACE.

Design No. 3,833, dated February 1, 1870.

DESIGN FOR SASH OR SHUTTER-LIFT.

The Schedule referred to in these Letters Patent and making part of the same

I, EMERY PARKER, of New Britain, in the county of Hartford, and State of Connecticut, have invented and produced a new and original Design for a Sash or Shutter-Lift, of which the following is a specification.

Reference is made to the accompanying photographic view, in which—

a designates a border of fret-work surrounding the oval cavity *A*.

The dark lines *b* designate sunken channels in the surface of the plate *B*, the fret-work being even with said surface.

The cavity *A* is surrounded by a wall extending back from the plate *B*, and nearly at right angles with the same.

Through this wall the screw-holes *c c* are made, by which the lift is secured to the sash or shutter, whereby the screws are not in an unsightly position, and therefore do not mar the appearance of the plate *B*.

I claim, as my invention—

The design for a sash or shutter-lift, substantially as described, and shown in the accompanying photographic view.

EMERY PARKER.
